DESIGN FOR A WAISTCOAT

Eddie Bauer, Seattle, Wash.

Application October 26, 1943, Serial No. 111,502

Term of patent 14 years

(Cl. D3—4)

To all whom it may concern:

Be it known that I, Eddie Bauer, a citizen of the United States, residing at Seattle, in the county of King and State of Washington, have invented a new, original, and ornamental Design for a Waistcoat, of which the following is a specification, reference being had to the accompanying drawing forming a part thereof:

I claim:

The ornamental design for a waistcoat, as shown.

EDDIE BAUER.
